CLAIM

The ornamental Design for a shoulder for a tire, as shown and described.

DESCRIPTION

FIG. 1 is a perspective view of a shoulder for a tire showing our new design, it being understood that the pattern repeats uniformly throughout the circumference of the tread;

FIG. 2 is a front elevational view thereof;

FIG. 3 is a right elevational view thereof; left side elevational view being identical thereto; and,

FIG. 4 is an enlarged fragmentary view thereof.

In the drawings, the broken lines immediately adjacent to shaded surfaces define boundaries of the claim; all other broken lines depict environmental subject matter only and form no part of the claimed design.
